UNITED STATES PATENT OFFICE.

JOHN DROWN, OF HURON, NEW YORK.

CONSTRUCTION OF POSTS FOR FIELD-FENCES.

Specification of Letters Patent No. 22,712, dated January 25, 1859.

To all whom it may concern:

Be it known that I, JOHN DROWN, of Huron, in the county of Wayne and State of New York, have invented a new and useful Improvement in Portable Fences; and I do hereby declare that the following is a full and exact description thereof, reference being had to the accompanying drawings, making part of this specification, Figure 1 being a side elevation of a portion of a fence constructed in my improved manner; Fig. 2, a top view thereof; Fig. 3, a transverse vertical section thereof in the plane indicated by the line $x\ x$, Figs. 1 and 2.

15 Like letters designate corresponding parts in all the figures.

The sections of the fence are formed of simple rails A, A, connected together by upright pickets a, a, or in any convenient 20 manner. The ends of each of the rails A, A, of adjacent sections, are halved together, as represented at b, b, so that they will present the uniform width of single rails. The ends of the lower rails, where joined together, rest in chairs B, B, of suitable length 25 and size to serve as a firm foundation for the fence. The notch or mortise c, (Fig. 3,) in the chair, which receives the ends of the lower rails, is made somewhat longer 30 than the width of the joined rails, and may have a dovetail form, as shown in Fig. 3; and the joined rails of the lower rails, which rest therein, are made, in that case, of a corresponding form. A wedge d, of 35 suitable shape, driven into the notch, beside the lower rails, holds them securely in place. Small notches are made in the outer edges of the upper rails at their joints, substantially as represented at f, f, Fig. 3.

40 These notches are made of sufficient width to admit the edges of the braces C, C, therein, and said braces may have corresponding notches g, g, in their inner edges, to receive

the rails. The braces project a little distance above the rails, where they are connected together by means of a clamp h, put over the ends of the braces, and fitting into small notches or holes i, i, in the braces; or any other equivalent means of firmly holding the braces together may be employed. One of the braces is secured firmly to the chair (as seen at k, k, Fig. 3,) so as to incline inward toward the fence. The other brace is then pressed inward and downward with some force, thereby firmly 50 tightening the rails, and making the fence firm and steady. When it is brought to a proper position, its lower end is secured to the chair by a single nail, screw, or hook, l, (Fig. 3.) The fence may be further tightened at any time, if it becomes unsteady, by 55 removing the nail or screw l, and pressing the brace in more closely toward the center of the chair. It thus constantly acts as a powerful lever to hold the fence firmly and 60 closely, while its fellow brace particularly sustains the fence in its proper position.

The fence is readily taken down at any time by separating the lever braces from the chairs, and removing the keys which confine 70 the rails in the chairs, when the parts separate from one another.

What I claim as my invention and desire to secure by Letters Patent, is—

The arrangement of the braces C, C, one 75 fixed and the other hinged or pivoted thereto, in combination with the rails A, A, and chair B, substantially as herein specified.

The above specification of my improved fence signed by me this 11th day of October, 1858.

JOHN DROWN.
